UNITED STATES PATENT OFFICE.

ABRAHAM MALKIN, OF DETROIT, MICHIGAN.

COIN-CONTROLLED MACHINE.

Application filed April 24, 1922. Serial No. 556,259.

This invention relates to means for operating article-delivery devices after the insertion of a predetermined number of checks or coins, and its object is to provide a coin-controlled mechanism whereby the positioning of a stop determines the number of coins which must be deposited before the article-delivery device can be operated.

A further object of this invention is to provide a coin-controlled mechanism which will deliver a predetermined number of coins of lower value when a coin is inserted of higher value than the selling price of the article which is to be sold.

Another object of this invention is to provide a simple and efficient coin-controlled mechanism which will stand rough usage without getting out of order.

In the accompanying drawings, Fig. 1 is a right side elevation of the coin-controlled mechanism when removed from its case. Fig. 2 is a left side elevation and Fig. 3 a front elevation of this mechanism. Fig. 4 is a left side elevation when the main supporting plate is removed. Fig. 5 is a view similar to Fig. 1 with partial cover plates removed. Fig. 6 is a section on the line 6-6 of Fig. 1. Fig. 7 is a detail showing the change-testing key. Figs 8 and 9 are diagrams of the change releaser in two positions. Figs. 10, 11, 12 and 13 are sections on the lines 10-10, 11-11, 12-12 and 13-13 of Fig. 1 respectively.

Similar reference characters refer to like parts throughout the several views.

The mechanism shown in the drawings is intended to be attached to any desired type of article-delivery mechanism which is actuated or controlled by a manually operated lever that actuates the several parts of this coin-controlled apparatus. This lever is normally prevented from moving a sufficient distance to operate the other mechanism by a swinging frame, but this control frame is rendered inoperative by the insertion of the predetermined number of coins of lower denomination or upon the insertion of a single coin of higher denomination, depending upon the sales value of the articles to be sold.

Provisions are made whereby the operating lever may be released by the insertion of the coin of higher denomination and the delivery of the proper number of coins of the lower denomination or the "change" should

the selling price of the article be below the 55 value of the coin of higher denomination. In the present case the coin of higher denomination is the nickel five cent piece and those of lower denomination are cents. Provisions are made to hold a number of cents in the 60 "change" receptacle so that "change" can be made for the nickel. This "change" receptacle is automatically filled when cents are deposited for operating the device. In the present case, the machine is set for articles 65 to be sold at three cents each and for the "change" maker to deliver two cents to the person inserting a nickel. Means are also provided whereby an intended purchaser may determine whether the "change" maker 70 has the proper number of cents to "make change".

The machine is built on a supporting plate 1 to which guide plates are attached and a partition plate and smaller cover plates are 75 attached to the guide plates. The cents pass down on the right side of the plate 1 and between it and the partition plate 2, while the nickels pass down on the right side of this partition plate. The movable parts of 80 this machine are actuated by an operating handle 3 which connects to the two side levers 4 and 5 which are mounted at their rear ends on a pin 6 extending through the several plates and guides. It is to be understood that one of these two levers may be omitted but that two are preferred as the 85 operation is more balanced.

Attached to the lever 4 on the left side of the machine is a pin 7 which represents the 90 connection between this coin-controlled mechanism and the article-delivery mechanism to which it is attached. Connecting rods 8 and 9 extend up from pins 10 on these levers to the pin 12 which extends through 95 guide slots 13 in the several plates and through holes in the coin pushers 14 and 15 which force down the coins.

In order to compel a full stroke of the operating lever, a rack bar 17 is attached to 100 the plate 2 and a pawl 18 is pivoted on the pin 19 on the lever 5, the pin extending through a block 20 on the outer side of the lever 5 and a finger 21 projecting rearwardly from this block and connecting to a spring 105 22 which is hung on the pin 23 on the lever 5. The pawl prevents the lever from being reversed until the pawl has entirely passed

over the rack so that it may be swung to extend from the opposite side of the lever 5.

On the plate 1 is an extension 24 on which the disk 25 is mounted, and on each side of the partition plate 2 are the runways 26 and 27 to receive the cents and nickels respectively. The plate 1 is provided with a slot 28 through which the cents may be observed. The partition 2 also has an extension 29 provided with a slot 30 and between this partition and the plate 1 are spacing and guide plates as follows. At the front and top is a spacer 31 which guides the pusher 14 and serves as the top of the "cent" race. Below it is a second spacer and guide plate 32 whose upper edge 33 and rear edge 34 are parts of the "cent" race, and which is formed with irregular rear edges 35 and 36 to co-operate with the front edges of the third spacer plate 37 to constitute the change receptacle consisting of the upright parts 38 and 39 and the inclined parts 40 and 41. The upper edge 43 and rear edge 44 of the plate 37 co-operate with the edges 45 and 46 of the fourth plate 47 to constitute a chute 48 for the cents not needed for making change, that is, after the change receptacle is filled, the cents roll down the chute 48 to the opening 49 and down the guide 50 to the cash box.

Attached to the plate 1 is a cross bar 52 (Fig. 4) which carries a pin 53 on which the sale controller is suspended. A spring 54 (Fig. 1) connects to this controller and normally holds it forward. This controller consists of a bar 55 on which a series of screws 56 are rotatably mounted. These screws operate the nuts 57 to which the fingers 58 are attached and these nuts are slideable in notches 59 in this bar. A finger 60 is rigidly attached to the bar 55 below the fingers 58 and each finger has a beveled forward end. In the present case, the machine is set for three-cent sales. The third finger 58^a from the top is therefore moved inward into the upright portion of the "cent" chute. It may be said that the rear side of this chute is formed by the small plates 61 and 62 between which the fingers extend. The inner ends of the screws 56 are mounted in the bar 63 (Fig. 1).

When the parts are as positioned in Fig. 4, and three cents have been inserted in the slot 26 and rolled down to the positions indicated in dotted lines, a depression of the operating lever and of the pusher 14 will force the coins downward and cause enough pressure on the finger 58^a to swing back the sales controller.

Fig. 1 shows the operating lever swung down without a sufficient number of coins being placed in the coin receptacles to swing back the sales controller. The link 9 has a finger 66 which extends over the finger 67 on the arm 68 at the outside of the lower end of the sales controller. When the parts are

as shown in this figure, the operating lever cannot be depressed any further. But if a sufficient number of coins were previously supported by the finger 58^a, the depression of the lever would swing this controller and the arm 68 and finger 67 out of the path of the finger 66 before the finger 66 reached the position shown in Fig. 1, and full operation of the lever 5 is permitted. The full stroke device 17-18 now forces the lever to move down its full distance before it can again resume its normal position.

When a nickel is inserted, the mechanism shown in Fig. 5 is employed. The partition 2 has an extension 27 and to this plate and its extension the guide plates 70, 71, 72, 73, 74 and 75 are attached, forming a runway for the nickels extending from the collar 25 to the opening 76 in the partition, which opening registers with the opening 49 in the side plate 1. There is only one finger 77 extending into the upright portion of the runway from its support, the lever 55, into the paths of the nickels and this finger holds the inserted nickel until the coin is forced down by the pusher 15 at which time the coin swings the lever 55 to the right in Fig. 1 and carries the finger 67 out of the path of the finger 66. The plates 79 and 80 form the outer wall of this coin chute.

The change maker is operated by the inserted nickels and controls the cents in the change receptacle. A pin 82 is mounted in the partition 2 and in a small plate 83 shown in Fig. 1. A lever 84 is mounted on this pin and has a flat thin head 85 at its upper end in the plane of the runway for the nickels, the lever itself being somewhat thicker. The spring 54 connects to the pin 86 and holds the head 85 in the path of the nickels but permits the lever to swing to the position shown in dotted lines in Fig. 5.

Mounted on the lower arm 87 of this lever are a series of screws 88 which extend through slots 89 in the partition plate and these screws are of such length that their inner ends are adapted to extend into the change receptacle. See Fig. 11. Springs 90 on these screws prevent them from turning. As the article to be sold is to bring three cents, two cents are to be given in change for each nickel inserted and therefore the point of the next to the lowest screw 88^a is moved into the change receptacle.

Three cents in the change receptacle are normally supported by a disk 92 rotatable on the pin 93 between plates 1 and 2 and rotatable by means of the crank pin 94 rigidly connected to the disk 92 and extending through the slot 98 into the slot 95 of the arm 96 at the lower end of the arm 87 of the change maker. This arm 87 is guided by a bar 97 (Fig. 1) and the crank pin 94 extends through a slot 98 in the partition 2. The lower end of the bar 9 may be guided

by a plate 99 but it is spaced farther apart from the plate 2 than the change maker and so does not interfere therewith.

The pin 94 which is mounted in the disk 92 and extends through the slot 98 in the partition 2 and through the slot 95 in the arm 96, projects far enough beyond this arm to be in the plane of the lower end of the bar 9. When a nickel is inserted and is pressed down by the part 15 against the head 85, this pin will be swung to the position shown in dotted lines in Fig. 5 before the lower end of bar 9 reaches the path of this pin. Thereafter the bar passes down to the left or in front of this pin in Fig. 1 and prevents the return of this pin until the operating lever has made full down and up strokes. This gives ample time for the "change" to pass down the passage 39 and out through the guide way 102.

When cents are inserted, the arm 87 is not swung, and the bar 9 is moved down so that its lower end passes back of the pin 94 (to the right thereof in Fig. 1). So long as the operating lever is making its down and up strokes, this pin and the disk 92 are kept from moving so that the "change" receptacle is kept closed by this disk and no discharge is permitted while the bar 9 is down.

When the nickel is forced down by the pusher 15, the coin swings the lever to the position shown in dotted lines in Fig. 5 and this carries the disk 92 from the position shown in Fig. 8 to that shown in Fig. 9.

In Fig. 8 this disk is shown supporting a series of cents A, but when the change maker is operated, this disk is turned until its straight side 100 is vertical and thus permits the discharge of the cents.

When the arm 87 and the screws 88 are swung toward the change receptacle, the depressed screw 88^a moves into the space between the second and third cents from the bottom and prevents all but two of the cents from falling out until the disk 92 is again in normal position. The number of cents to be given in change is therefore determined by the screws 88 and the number of cents the article is to bring is determined by the screws 56. The change goes down the chute 102 into the small receptacle 103 from which it can be removed by the purchaser.

If the wall 34 were straight down to the edge 35 of the plate 32, the cents along the edge 43^a might pile up until above the point 45^a which would cause clogging of the machine. The vertical edge 34 of the plate 32 is therefore cut back at 34^a and the edge 43^a is advanced so that the upper coin C is not in alinement with the coin chute above it but a little on one side of this chute. Descending coins normally strike the corner 43^b and swing toward the edge 34^a, and when the coin receptacle is filled, the upper coin C is at one side of the path of the next coin

which rolls off and down the chute between the edges 43 and 45. The corner 34^b is preferably at the height of the middle of a coin contacting with the upper coin C in the coin receptacle.

Figs. 4 and 7 show the details of a device for determining if there are sufficient coins in the change receptacle. A button 104 on the rod 105 is adapted to push the rear end of this rod against a coin. A small plate 106 is mounted on the pin 108 and has a curved plate 110 at its outer edge (Fig. 3). This plate 106 is connected to the rod 105 by a pin 111 and the parts are held in the position shown by the spring 112. Any desired letters may be placed on the curved plate 110, to be shown when the rod 105 strikes a coin or when it is unobstructed and moves entirely inward.

As stated before, the side plate 1 has an extension 24 and a slot 28, the partition 2 has an extension 29 and a slot 30, and the plates 31 and 32 are between the plate 1 and the partition 2 and form a runway 33. Secured to the partition 2 are the plates 70 and 71 and they form the runway 69, and the plate 79 is secured to these plates and has a slot 78. See Fig. 9. Attached to the plate 79 is an apron 114 on which rejected coins may slide out of the machine.

When a cent is placed into the runway 33 it will roll into the machine, but a dime will slip out sidewise. A nickel will roll into the machine in the runway 69 but smaller coins will fall out sidewise onto the apron 114 and slide out of the machine. This mechanism therefore prevents the insertion of a coin of improper value. This device also prevents the insertion of wires, pins and other improper articles sufficiently far to operate or clog the mechanism shown in the drawings, as such articles will also slip out sidewise through the slots in the plates 2 and 79 onto the apron 114.

The details and proportions of the several parts of this device may all be changed by those skilled in the art without departing from the spirit of my invention as set forth in the following claims.

I claim:

1. In a coin controlled machine, the combination of a chute to receive coins, a movable controller, stops thereon adapted to be positioned to determine the number of coins necessary to cause operation of the machine, and a manually operated device normally prevented from operating by said controller adapted to engage the last inserted coin to move the controller out of engagement with said manually operated device.

2. In a coin controlled machine, the combination of a chute to receive coins, a movable controller, a stop thereon adapted to be positioned to determine the number of coins necessary to cause operation of the machine,

and a manually operated device normally prevented from operating by said controller adapted to engage the last inserted coin to move the controller out of engagement with said manually operated device, and means to cause the manually operated device to make full strokes in both directions.

3. In a coin controlled machine, the combination of a chute to receive coins, a movable controller, a series of stops thereon adapted to be positioned to determine the number of coins necessary to cause operation of the machine, a manually operated device normally prevented from operating by said controller adapted to engage the last inserted coin to move the controller out of engagement with said manually operable device, said stops comprising fingers adapted to be moved into and out of said coin chute.

20 4. In a coin controlled machine, a coin receptacle, a chute leading thereto, a swinging controller, a series of stop fingers mounted thereon and adapted to be moved into said chute to determine the number of coins necessary to permit actuation of the mechanism, said controller embodying a stop arm, a lever pivoted on said machine, a link connected to the lever and a finger thereon normally adapted to engage the arm on said controller to prevent the operation of said lever, and means connected to said link to force down the coins in said chute to swing the controller and move said arm out of the path of the finger on said link.

35 5. In a coin controlled machine, a coin receptacle, a chute leading thereto, a swinging controller, a series of stop fingers mounted thereon and adapted to be moved into said chute to determine the number of coins necessary to permit actuation of the mechanism, said controller embodying a stop arm, a lever pivoted on said machine, a link connected to the lever and a finger thereon normally adapted to engage the arm on said controller to prevent the operation of said lever, means connected to said link to force down the coins in said chute to swing the controller and move said arm out of the path of the finger on said link, and a full-stroke device operatively connected to said lever to insure a complete operation of said lever.

6. In a coin controlled machine, a coin receptacle, a chute leading thereto, a second coin chute, a swinging controller, a stop finger thereon extending into the second coin chute to stop inserted coins, a lever having an end extending into the second chute, manually operable means to force down the coin in the second chute and swing the controller and said lever, and means connected to said lever for discharging a predetermined number of coins from said first named receptacle.

7. In a coin controlled mechanism, a plurality of coin chutes to receive coins of dif-

ferent denominations, a receptacle to receive and hold coins of lower denomination, means operating in the chute for coins of higher denomination to forcibly move the coins therein, and means actuated by said coins when forced along to discharge a predetermined number of coins of lower denomination.

8. In a coin controlled mechanism, a plurality of coin chutes to receive coins of different denominations, a receptacle to receive and hold coins of lower denomination, means operating in the chute for coins of higher denomination to force down the coins therein, means actuated by said coins when forced down to discharge a predetermined number of coins of lower denomination comprising a cam normally supporting said coins, a lever arm connected to said cam to turn the same out of the path of said coins, and a series of adjustable pins adapted to be swung into the path of said coins to predetermine the number to be released.

9. In a coin controlled mechanism, a plurality of coin chutes, a controller, stop fingers mounted thereon and extending into said chutes to stop the coins, an operating lever, normally engaging means on the lever and controller to prevent the operation of the lever, and means connected to the lever to force down the coins to cause the stops to swing the controller to carry the stops out of the paths of the coins and to carry the controller out of the path of the lever.

10. In a coin controlled mechanism in which a delivering device is rendered operative upon the insertion of a predetermined number of coins of one size into a coin chute and upon the insertion of one coin of a second size into a second coin chute, manually operable means to actuate the delivering device comprising two instrumentalities which are normally disconnected but are adapted to be operably connected by a coin of the second size, and mechanism actuated by said instrumentalities when so connected to deliver a predetermined number of such inserted coins of the first size from the first named coin chute.

11. In a coin controlled mechanism for vending machines, a plurality of coin chutes adapted to receive coins of different sizes, one of said chutes being adapted to receive and retain the inserted plurality of coins of one size after the article delivery mechanism has been operated under the control of said inserted coins, manually operated actuating means for the vending mechanism controlled by said plurality of said inserted coins, means connected to said actuating means and controlled by a coin of the second size when in its chute to remove a predetermined number of such inserted coins of the first size from the chute which received them.
